ADDING AND CALCULATING MACHINE

Louis M. Llorens, New York, N. Y., assignor, by
mesne assignments, to George Moore, Hastings
on Hudson, N. Y.

Application February 3, 1931, Serial No. 513,112
Renewed September 3, 1937

14 Claims. (Cl. 235—60)

This invention relates to adding and calculating machines, and the principal object is to produce a device of this nature which will be portable. To this end, incidental objects have been 5 to use few parts, simple of construction, and each performing as much work as possible. Other objects have been to provide novel and simple differential mechanism, two-way carry mechanism, sign printing mechanism and various 10 controls. Many other objects will appear from the following description and claims. The mechanism for this purpose is shown in the accompanying drawings made from a full size operating machine.

15 In the drawings:

Fig. 1 is a top plan view of a machine embodying my invention.

Fig. 2 is a right side elevation of the same.

Fig. 3 is a front elevation of the same.

20 Fig. 4 is a right side elevation just inside the cover.

Fig. 5 is a top plan view with the cover and paper carriage removed.

Fig. 6 is a horizontal sectional view taken substantially on line 6—6 of Fig. 4.

Fig. 7 is a bottom plan view with base-plate removed.

Fig. 8 is an elevation of the right side frame member with certain of the parts associated 30 therewith.

Fig. 9 is a vertical section substantially on line 9—9 of Fig. 5.

Fig. 10 is a left elevation with the cover removed and the base and air-pot in section.

35 Fig. 11 is a vertical section substantially on line 11—11 of Fig. 5.

Fig. 12 is a vertical section substantially on line 12—12 of Fig. 5.

Fig. 13 is a vertical front-to-rear section taken 40 substantially thru the center of the machine, parts being shown in operated position.

Fig. 14 is a vertical section taken substantially on line 14—14 of Fig. 5.

Fig. 15 is a similar view taken substantially 45 on line 15—15 of Fig. 5.

Fig. 16 is a fragmentary perspective view of the "1" slide bar.

Fig. 17 is a detail sectional view of the carriage indicator.

50 Fig. 18 is a vertical sectional view taken just inside the right-hand main frame plate.

Fig. 19 is a fragmentary perspective view of part of the total detent mechanism.

55 Fig. 20 is a vertical sectional view taken sub-

stantially in the plane of the left face of the right-hand intermediate plate.

Fig. 21 is a fragmentary detail section substantially on line 21—21 of Fig. 20.

Fig. 22 is a detail view showing principally the 5 ribbon mechanism.

Fig. 23 is a vertical section of the paper carriage taken just inside the left-hand frame thereof and looking toward the right.

Fig. 24 is a similar view taken substantially 10 thru the middle of the carriage and looking toward the left, parts being broken away for the sake of clearness.

Like reference characters refer to like parts in all views. 15

Main framework (Figs. 1 to 6)

The main framework of the machine includes a cover 100 which encloses most of the working parts of the machine and is provided with a 20 sight-opening covered with a window 101 thru which the accumulator dials may be read. This cover rests upon a base plate 102 and is removably secured thereto by screws or other suitable means. 25

Rising from the base plate 102 are right and left side plates or frames 103 and 104 which are secured together and spaced apart by tie rods and tie plates, the essential ones of which will be hereinafter indicated by reference characters 30 as the parts with which they are associated are described.

Beside the above frame elements there are also right and left intermediate plates or frames 105 and 106 which are secured to the plates 103 and 35 104 by tie rods.

Upon these several frame members are supported all of the working parts of the machine.

Numerical keys (Figs 1 to 13)

The keyboard includes six special keys and ten digit keys 107. Each of the digit keys 107 is inscribed with its proper digit. Each significant digit key is secured to a respective key-lever 108 pivoted on a pivot rod 109 supported by the frame plates 103 and 104 of the machine. The "0" key is provided with two key-levers 110 which are also pivoted on the pivot rod 109. The several levers pivoted on rod 109 are spaced apart by suitable spacing collars 111. Suitable springs 112 are connected to the key-levers 108 and 110 and support the same and return them to normal condition after each key-stroke. Springs 112 are anchored to a tie rod 113 which extends between frame members 103 and 104. 40 45 50 55

The several key-levers 108 and 110 are guided in slots 114 formed in a comb-plate 115 secured to frame members 103 and 104. The upper boundary of the slots is paralleled by a leather stop member or bumper 116 secured to the inner face of the comb-plate 115, and this bumper limits the upward movement of all the key-levers and cushions their blow as well as eliminating considerable noise. A tie rod 117 passes from frame member 103 to frame member 104 under the key levers; and carries a rubber tube 118 which limits depression of the keys, cushions their blow, and eliminates noisy action.

Numerical key interlock (Figs 4, 6, 7, 9 to 16)

Means are provided for preventing the simultaneous depression of a plurality of digit keys and for preventing depression of any digit key when another digit key is in depressed position.

Secured to the inside of each of the side frame members 103 and 104 are comb plates 119 and 120 which are spaced slightly from the respective frame members by slotted blocks 121. The slots in the combs and blocks are in alignment and serve to guide and space apart nine slotted control slides 122, each of which is adapted to be moved from right to left by a respective digit key lever. The foremost slide 122 is controlled by the "1" key-lever 108, and so on, so that the rear-most slide 122 is controlled by the "9" key-lever.

Each slide 122 is formed with a slot 123 for each of the key levers 108 and 110 and also with a slot 123 for the Non-print key lever (to be later described), and has its left end cut down to abut the "Back-space key-lever (to be later described) if the same is depressed. The slots 123 of the several slides 122 are normally aligned with the several key-levers and the slot of any slide which receives the key of its own digit value is slightly widened toward the right; and a roller 124 is supported on the slides so as to be contacted by the respective key lever. Depression of any significant digit key-lever causes the latter to strike the roller 124 of its respective slide 122 moving the latter to the left far enough to bring its slot other than the wide one for the depressed key-lever, out of registry with the remaining several key-levers, so that no other key connected with the system may then be depressed until the depressed key returns to normal. When simultaneous depression of a plurality of keys is attempted, the respective slides are moved by their rollers and all keys are locked against effective depression until all but one are returned to normal.

The "0" key-levers 110 and the Non-print key lever merely move into aligned slots 123 upon depression so that none of the slides 122 may be moved by a significant digit key; and the Back-space key-lever moves down to the left of all the slides 122 with similar results. Springs 125 return the slides 122 to their right-hand or normal position and movement in this direction is limited by stops 126 formed on the slides 122 contacting the guide member 119.

Effect of depressing a digit key

Before going into details as to the effects produced by depression of a digit key, it may be well to consider the matter generally.

Depression of a significant digit key trips an escapement mechanism so as to permit a very slight movement of a preliminary representation carriage; throws a tiltable pinion into mesh with one or another of a plurality of racks on said

carriage; trips a detent for the engaged rack so as to permit the same to move; moves the respective slide bar 122 so that its left end intercepts a universal slide bar, and causes the tiltable pinion to limit movement of the engaged rack; and locks the universal slide-bar against retrograde movement or chattering.

Return to normal of a depressed significant digit key causes the tiltable pinion to move out of engagement with the engaged rack; the detent to return into engagement with such rack; the digit slide bar 122 to return to normal; the universal slide bar to be unlocked and returned to normal; and trips the escapement back to normal so as to permit the preliminary representation carriage to complete one denominational step of movement.

Depression of the "0" key, locks the significant digit keys as already explained, and trips the escapement so as to permit a slight movement of the preliminary representation carriage. Return of this key trips the escapement back to normal so as to permit the preliminary representation carriage to complete one denominational step of movement, and unlocks the other digit keys.

With this general statement we shall pass to a consideration of these features in detail.

The preliminary representation carriage (Figs. 6, 7, 8, 9, 11, 12, 13, 14)

There is provided a carriage upon which a preliminary representation of items is set up by action of the keys prior to the entry of such items on the register. This carriage consists essentially of a carriage frame formed from a single piece of sheet metal bent so as to have legs 127 and 128 connected at their rear ends by a portion 129. The front ends of legs 127 and 128 are connected by a bar 130.

Secured to the front ends of legs 127 and 128 are grooved wheels 131 which ride on top of a tie rod 132, and rollers 133 which underlie the said tie rod 132. The portion 129 carries a roller 134 which rides on a rear tie rod 135, and a finger 136 which underlies such rod. Finger 136 is not formed directly on portion 129 but is bent out from an intermediate carriage frame 137 which is secured to portion 129 and bar 130. By this construction the carriage frame is secured against possible movement in any direction laterally of the tie rods 132 and 135 but is free to move therewith, i. e., axially thereof.

A spring 138 tends constantly to drive the carriage from right to left as viewed from the front of the machine, and such movement is controlled by escapement mechanism which will now be described.

Carriage escapement (Figs. 6, 7, 9, 11, 12, 13)

The preliminary representation carriage is provided with a suitable step-by-step escapement stop mechanism, whereby the carriage is properly positioned for receiving digital values of the several desired denominational orders.

The key-levers 110 of the "0" key are adapted to engage with a short yoke 139 pivoted on the rod 109. The key-levers 110 of the "0" key are cut away so as not to engage a second yoke and longer yoke 140 also pivoted on rod 109 and which longer yoke extends under all of the key-levers 108 of the significant digit keys 107. Yoke 139 is formed with a lip 141 underlying the long bail 140. It will thus be seen that when a significant digit key is depressed, both of the bails 139 and 75

140 will be rocked, while when the "0" key is depressed only the short bail 139 will be rocked.

Whenever the short bail 139 is rocked, it pushes rearwardly a link 142, the forward end of which is pivotally connected to the bail 139, and the rear end of which, is pivoted in the lower end of a stud 143 depending from a cross-bar 144 pivotally mounted in the side main frames 103 and 104 of the machine. The rearward movement of link 142 therefore effects rocking of the bar 144 against the tension of a spring 145 which normally holds the bar 144 with a lug 146 formed thereon in contact with a stop-pin 147 projecting from the frame 104. Spring 145 is anchored to a pin 148 projecting from the frame 103, and in holding bar 144 in normal position, also maintains link 142 and bail 139 in normal condition. The rocking of bar 144 is limited by a finger 149 engaging the top of pin 147.

20 The bar 144 is formed with a rigid stop tooth 151, and carries a movable stop pawl 152 the movement of which in one direction is positively limited by a rigid pin 153, and is variably limited in the other direction by a lip 154 formed on the 25 end of a pivoted stop member 155 also pivotally carried by the bar 144. The normal position of the stop member is determined by a finger 156 of the same engaging the front edge of the bar 144, being urged into such engagement by a spring 30 157. The escapement stop pawl 152 is constantly urged toward the stop 154 by a spring 158, the tension of spring 157 being stronger than that of spring 158.

Normally, the movable stop pawl 152 is in engagement with a ratchet rack 159 which is rigidly secured to the carriage frame to move therewith. When the bar 144 is swung by the depression of one of the digit keys, the pawl 152 is withdrawn from the rack 159 and the rigid stop tooth 151 is engaged therewith, thereby permitting the carriage to move very slightly, the stop face of the rigid tooth 151 being normally slightly to the left of the stop face of the pawl 152. As soon as the pawl 152 is disengaged from the rack 159, its spring 158 causes it to move until it engages the lip 154, which holds the pawl 152 against further movement owing to the relative strengths of the springs 157 and 158. Upon releasing the depressed key, the plate 144 is swung back to normal by its spring 145 and thereby the movable pawl 152 is again engaged with the escapement ratchet rack 159 and tooth 151 is disengaged, whereupon the spring 138 draws the carriage to the left the rest of one denominational step until the pawl 55 152 again strikes the rigid stop 153.

In returning the carriage either for back-space operations or for carriage return operations as will be later described, the stop 155 permits the stop pawl 152 to be moved by the ratchet bar 60 against the finger 154 and to rock the stop member 155 so that return movement of the carriage may be effected. Except for this, the stop finger 154 might be a pin.

Differential stop mechanism (Figs. 6, 7, 9, 11, 12, 13)

65 The preliminary representation carriage carries a series of differential stop members 160, there being one for each denomination for which the machine is designed. In the present showing the machine is designed for a capacity of nine digits or denominational places in any one item, and hence nine differential stop members 160 are shown, altho more or less could be used to satisfy 70 the requirements which the machine is built to fit.

The several differential stop elements 160 are slotted at their front ends as at 161 such slots receiving the carriage rail 132 and the upper and lower fingers at these slots being guided and supported in double combs cut in the carriage cross-bar 130. The rear portion of each differential stop member 160 is formed with a slot 162 which embraces a tie rod 163 passing from the leg 127 of the carriage frame to the intermediate frame 137 thereof. The rear ends of the several differential stop members 160 are guided in slots or a comb cut in the rear portion 129 of the carriage frame.

Each differential stop member 160 is constantly urged rearwardly by a respective spring 164, and 15 is normally restrained by a respective restraining dog 165 mounted pivotally on a rod 166 supported by ears rising from the right leg 127 and the intermediate carriage frame member 137. Each dog 165 is formed in the shape of a bail having 20 an engagement tooth 150 in the plane of the respective differential stop member 160 and a releasing finger 167 lying in the plane next adjacent toward the right. As the carriage is stepped from right to left, one after another of the releasing fingers 167 is brought under a releasing element 168 operable by the significant digit keys as will presently be set forth. Individual springs 169 tend constantly to throw the respective dogs into rack engaging position. The several differential stop members 160 are formed with racks 25 170 which co-operate with the dogs just mentioned, and also with other instrumentalities presently to be described.

Each differential stop member 160 is also 35 formed with a series of ten stop shoulders 171 arranged in step formation and indicating from top to bottom the digits "0" to "9", the lowest or "9" step being cut away for clearance of other parts. These ten steps of each member control 40 the extent of actuation of the actuating rack and type carrier with which they are caused to co-operate.

Tiltable pinion (Figs. 6, 7, 9 to 13)

45 Means is provided for releasing the differential stop bars seriatim and for controlling the extent of movement of the same in accordance with the value of the digit key which effects the release of the same.

50 Secured to the left-hand side of the long bail 140 operable by the significant digit keys is a depending finger or arm 172 to the lower end of which is pivoted the front end of a link 173, the rear end of which is pivoted to the lower end of an arm 174 the hub of which is secured to a shaft 175 having its bearings in the left side frame 104 and in the right hand one 105 of two intermediate machine frames 105 and 106. A spring 176 tends constantly to draw link 173 forward and to 55 hold the associated parts in normal position.

55 Rigidly secured to the shaft 175 near the intermediate frame member 105 is a forwardly extending arm 168 the curved front end of which normally over lies the releasing finger 167 of the 60 left-hand retaining dog 165 (the retaining dog of the leftmost differential stop member).

65 Freely mounted in the front end of the arm 168 is the right-hand end of a tiltable shaft 178, the other end of which is freely rotatable in the 70 main frame 104. Collars or other suitable means may be utilized to prevent endwise play of the shaft 178. Secured to the tiltable shaft 178 near its right-hand end is a pinion 179 which normally lies in the plane of the leftmost differential stop 75

member 160 and consequently in line with the rack 170 thereof. Secured to the tiltable shaft 178 near its left-hand end is a pinion 180 which constantly meshes loosely with a rack 181 on a universal slide bar 182. This universal slide bar 182 is formed near its front end with a rearwardly facing stop 183 and with a spring element 184, and is constantly urged forwardly by a spring, 1820.

10 When a significant digit key is depressed, the rocking of the frame 140 causes rocking of the depending arm 172 which in turn forces rearwardly on link 173, thereby rocking shaft 178 and arm 168. In this rocking, the front end of arm 168 engages the releasing finger 167 of the dog 165 releasing the corresponding differential stop member 160. Simultaneously the shaft 178 has been tilted so as to bring its pinion 179 into engagement with the rack 170 of the released differential stop member 160, the latter now moving rearwardly under the influence of its spring 184 and effecting rotation of pinion 179, tiltable shaft 178 and pinion 180. This causes the universal rack bar 182 to be moved rearwardly against the tension of its spring until its stop 183 engages the end of the digit slide 122 which has been moved by the depressed digit key. Differential stop bar spring 184 is stronger than universal slide bar spring 1820. At this instant the spring element 184 jumps in at the rear of the digit slide 122 thereby preventing any appreciable rebound.

When the key is released, the dog 165 is released and engages the rack 170 holding the same in the position to which it has been moved, the digit slide 122 unlocks the universal slide 182 and permits the latter to move back to normal under the influence of its spring 1820 and this slide rotates pinions 179 and 180 and shaft 178 accordingly.

45 In case the "0" key is depressed, the differential stop member is not released and none of the above occurs: but whether a significant digit key or the "0" key is operated, the carriage is stepped at the end of the operation as already explained so as to bring the next differential stop member to the right into cooperative relationship with the pinion 179 and releasing arm 168.

50 **Back space mechanism (Figs. 1, 3, 4, 6, 7, 9, 10, 11, 12, 13)**

It may at times be desirable to back-space the preliminary representation carriage as in division; and the following means is provided for this purpose.

Secured to the carriage escapement ratchet rack 185 and spaced apart therefrom by posts or other suitable means is a back-space ratchet rack 185. A pawl or a dog 186 adapted to cooperate with the teeth of the rack 185, is pivotally mounted on the rear end of a bell-crank lever 187, and is constantly urged toward engagement with the rack by a spring 188. This engagement is normally prevented by the heel 189 of the pawl 186 being forced against a stop pin 190 carried by a plate 191. Movement of the pawl 186 and its bell-crank 187 toward the right, is limited by engagement of the pawl with a pin 192, also depending from the plate 191. A spring 190 tends constantly to draw the bell crank 187 in a clockwise direction as viewed from the bottom.

75 The bell-crank 187 is pivoted at 193 to the plate 191 and has its short arm 194 pivotally connected to a link 195 which has its rear end

pivoted to the lower end of a depending arm 196 of the back-space key-lever 187, operable by button 198 and held up by spring 192.

When the back-space key is depressed it swings the bell-crank 187 thereby bringing the pawl 186 into engagement with the rack 185 and then carrying the rack and the preliminary representation carriage back something over one space, the movable pawls 152 and 155 of the escapement permitting this movement; and, upon releasing the key, the parts return to normal, leaving the carriage set one space to the right, however.

This mechanism is purely a back-space device for division or other purposes, and not to be confused with correction or error keys in the prior art which have frequently been erroneously denominated as "back space keys".

Carriage position indicator (Figs. 1, 3, 5 and 10)

Secured to the left-hand leg 128 of the carriage frame, is one end of a cord or the like 200, which passes over a grooved pulley 201, pivotally mounted on a pin from the left-hand main frame member 104. The cord 200 then passes forwardly at the left side of the machine and is secured to a drum 202 rotatably mounted on a pin 203 extending from the left frame 104 of the machine. The drum 202 carries an indicator dial 204 having numerals engraved or otherwise indicated thereon, and visible, one at a time, thru an opening 205 in the casing. This dial is a tight fit for the drum but may be adjusted thereon by hand so as to bring the same into proper indicating position relative to the drum.

A coiled spring 206 is located inside drum 202, with one end anchored to the right-hand end of the drum, and the other end secured to a washer 207 secured to the left end of pin 203 and snugly held against it by a screw 208. By loosening up on screw 208 and rotating the washer 207 more or less tension may be given to spring 206. The drum 202 is far enough from washer 207 so that, while the washer is secured against rotation by spring 206 the drum is free to be rotated thereby.

As the carriage is stepped from right to left, spring 206 is permitted to turn drum 202 to take up the slack in cord 200, and thus the dial 204 is turned so as to indicate the extent to which the carriage has been moved.

Operating lever and main shaft (Figs. 1 to 5 and 7 to 15)

The operating mechanism of the machine includes an operating handle or hand-crank 209, the hub 210 of which is centrally apertured to receive a screw 211 which threads into the right-hand end of the main shaft 212. The hub 210 also carries dowel pins 213 which engage in apertures 214 in a collar 215 pinned or otherwise fixedly secured to the main shaft. In this manner the operating lever is removably, but rigidly secured to the main shaft.

The forward stroke of the operating lever may be very rapid, but the end of the return stroke is preferably cushioned so as to prevent jar. For this purpose, I connect an air-pot device to the main shaft, the construction being as follows:

Secured to the left-hand end of the main shaft 212 outside frame 104, is a downwardly extending rock arm 216, which carries at its free end a spring-holder 217 to which a stout return spring 218 is secured, the front end of such spring being anchored to a pin on the base plate 102. This spring serves to return the main shaft to normal after a forward stroke of the operating lever.

Fixedly secured to the main shaft 212 is a rock arm 219. A short rod 220 is fastened at opposite ends to the rock arms 216 and 219, and to this rod 220 is pivotally connected the lower end of an upright link 221. The upper end of link 221 is pivotally secured to the central portion of a lever 222, one end of which extends forwardly and is bent into a yoke as at 223, where it is pivotally secured to the main frame 104. The rear end of lever 222 is pivoted to the upper end of the air-pot plunger-rod 224.

The air-pot proper, includes a body portion 225 pivoted in a support 226 secured to the base plate 102, and a cover 227 which is threaded to the top of the body 225. This cover is provided with an aperture 228 to permit free ingress and egress of air, and also with a central aperture thru which the plunger-rod 224 passes.

At its lower end, plunger-rod 224 is reduced and carries a piston 229 having a long apron and fitting snugly in the body 225. It is particularly necessary to have the piston 229 long so as to prevent more effectively any air escape, and to have it hollow so as to give the greatest air capacity, in order that the dash-pot may be made small for a portable machine such as the present. The plunger or piston 225 is formed with an air inlet as at 230. A nut 231 is threaded on the bottom of rod 224 and holds the piston 229 firmly in place. Mounted on the shank of nut 231 is a leather washer 232 which is pressed by a spring 233 against the inner upper face of piston. This washer permits ready ingress of air thru opening 230, but prevents egress of air there-thru.

The body 225 of the air pot has an opening 234 drilled in its lower end and fitted with a screw 235. There is also a by-pass 236 drilled into opening 234. By adjusting the screw, the rapidity of egress of air thru the upper part of opening 234 and by-pass 236 may be controlled, and the speed of the return stroke thereby controlled.

Actuators and their control by differential stop members (Figs. 6, 7, 9, 11, 12 and 14)

The actuators are indicated at 237 and are pivotally mounted on a shaft 238 having bearings in all four frame members 103, 104, 105 and 106. Passing from one side frame 103 to the other 104, is a stout tie bar 239 to which are attached blocks 240 which are secured to and help support the intermediate frame members 105 and 106. This bar 239 and blocks 240 also support a comb plate 241 having apertures, one for each actuator. Thru each of these openings in the comb plate 241 extends a stop bar 242 depending from a respective actuator 237.

Each stop bar 242 is formed with a forwardly projecting ear 243 which carries two depending springs 244 secured to respective sides of a spring anchor channel bar 245 carried by a movable rod 246.

Rod 246 is supported at opposite ends by links 247, and guided in slots 248 formed in plates 249 carried by blocks 240. The upper ends of links 247 are attached to the front ends of respective rock levers 250 freely pivoted on actuator shaft 238. The rear ends of rock levers 250 are pivotally connected to depending links 251 having their lower ends pivoted to arms 252 fast on the main operating shaft 212.

When the operating lever is drawn forwardly, the shaft 212 is rocked, thereby causing arms 252 to raise links 251, rocking levers 250 and depressing links 247, whereby rod 246 is depressed, straining springs 244 which are normally under

only a slight tension. This draws stop bars 242 down until they strike the respective differential stop bars 160, coming to rest on the positioned stops 171. Thus the extent of the excursions of actuators 237 is controlled, and consequently that of actuator racks 253 formed on the front ends thereof.

A pivot rod 254 is secured between the left leg 128 and the intermediate frame 137, and pivotally supports a rockable bar 255, the ends of which are bent into ears 256 which are pivoted on rod 254. The right-hand ear 256 is formed with a lip 257 carrying a pin 258 which extends thru a slot 259 in the rear end of a curved arm 260 fast on a shaft 261 mounted in bearings in ears 262 bent up from plates 263 which tie the front ends of the pins carrying the carriage rollers 131 and 133. A spring 264 coiled about shaft 261 has one end anchored to the left-hand ear 262 and the other pressing arm 260 clockwise as viewed from the right. Normally this spring and arm 260, rock the bar 255 forwardly so that it stands in line with the "0" stops 171 of the bars 160, and prevents downward movement of all bars 242 to the left of the left-hand bar 160 in all moved positions of the carriage and of all bars 242 when the carriage is in its initial or right-hand position.

The accumulator frame (Figs. 4, 5, 8 to 15)

Mounted freely on a shaft 265 supported in the main side frame-members 103 and 104, are right and left accumulator frame plates 266 and 267 which are spaced apart and secured together by upper, intermediate and lower tie rods 268, 269 and 270. This frame carries the accumulator shaft 271 which extends there-beyond into openings in the main frame members 103 and 104. The accumulator frame normally stands forward, with the right-hand end portion of the accumulator shaft 271 in the bottom of a slot 272 formed in a cam lever 273 pivoted to the right side frame 103.

By rocking cam lever 273 counter-clockwise, as viewed from the right, the contour of slot 272 will cause the accumulator shaft 271 to be forced rearwardly, thereby rocking the accumulator frame rearwardly (clockwise as viewed from the right), by which movement the accumulator gears are brought into mesh with the racks 253. Disengagement is effected by rocking cam lever 273 clockwise back to normal. The means for rocking cam-lever 273 will be hereinafter described.

The accumulator (Figs. 5, 9 to 13)

The accumulator construction is extremely simple. Mounted for free rotation on the accumulator shaft 271, is a plurality of accumulator gears 274, one for each actuating rack 253, and secured to the left side of each gear 274 is an accumulator dial 275 which preferably carries one set of ten digits "0" to "9". The digits of the dials are exposed one at a time thru openings in a dial plate 276 carried by the accumulator frame plates 266 and 267. Secured to the left side of each dial 275 is a carry pin 277 for use in effecting carrying or tens-transfer as will be later fully set forth. These pins also determine the resetting of the dials to zero position.

Carrying mechanism (Figs. 8 to 15)

The carrying or tens-transfer mechanism is capable of turning the wheels carried to, in either direction, thus effecting additive or subtractive transfer; but as the additive transfer is normally

effective, we shall for the present, confine ourselves, as far as possible to additive transfer.

- 5 Mounted freely on the lower tie rod 270 of the accumulator frame is a plurality of rockers 278, there being one between each pair of accumulator dials. The front ends of the rockers 278 are of yoke form so as to eliminate spacers and at the same time give the rockers broad bearings. Pivoted on each rocker 278 is an upstanding, large, 10 double-acting pawl, the additive carry arm of which is indicated at 279, and the subtractive arm at 280. The pawls 278-280 and rockers 278 are constantly urged upwardly by springs 281 secured at their lower ends to pawls 279-280 and 15 at their upper ends to a movable anchor rod 282.

In the normal position of anchor rod 282 the additive carry arms 279 are urged toward their respective accumulator gears 274. Each arm 279 and 280 terminates in a notched or toothed end 20 adapted to engage and turn the respective gear 274 one tooth, upon its rocker being released. Normally all rockers 278 are held down with their rear ends slightly below a rod 283.

Each rocker 278 carries a pin 284 extending to 25 the left and normally engaging under a shoulder 285 formed on the lower end of a carry-trip pawl 286. The several pawls 286 are pivoted on the intermediate tie rod 269 of the accumulator frame, and have noses 287 formed on their upper 30 ends in the paths of movement of the carry pins 277 of the lower denomination dials. Springs 288 normally tend to rock trip pawls 286 clockwise as viewed from the right. The upper ends of springs 288 are secured to detent pawls 289 pivoted on the 35 upper tie rod 283 of the accumulator frame and engaging the gears 274 so as to prevent over rotation.

The rear portions of rockers 278 underlying rod 283 are curved out as at 280, and these portions 40 are of different lengths so as to release the rockers 278, seriatim, beginning with the one at the right, when rod 283 is moved to release them. The rod 283 is faced off on its front side so as to effect abrupt movements of rockers 278 when 45 released.

The rod 283 is carried by the lower ends of two arms 281 pivoted to the frames 266 and 267 and carries the front ends of two links 292 slotted at 50 283 to ride on the reduced portions of collars 294 mounted on a thru tie rod 285. Springs 296 connect arm 281 and links 292 and tend constantly to throw the rod 283 forward to normal position. Secured to the rear ends of links 292 are rocking abutment pieces 297, the rocking movement of 55 which is limited by pins 298 mounted on the abutment pieces 297 and extending into notches 299 formed in links 292.

Fixedly mounted on the main shaft 212 are plates 300 which carry rollers 301 extending into the planes of abutment pieces 297.

In operation when a dial 275 completes a rotation, its pin 277 rides over the nose of a respective carry-trip lever 286, rocking the same so that pin 286 escapes from shoulder 285, permitting the respective rocker 278 to rotate slightly until its rear end rests against the rod 283. During the forward stroke of the operating handle 209 plates 300 have been rocked forward until rollers 301 stand well in front of abutment pieces 297. Well 60 along in the rear stroke, the rollers 301 engage abutment pieces 297 and carry them rearwardly, thereby moving links 292 and consequently rod 283 which latter releases the set rockers, seriatim. Each released rocker springs up carrying its pawl 70

arm 278 or 280 far enough to rotate the next higher gear one tooth, effecting carrying.

The released rockers 278 are returned to normal at the end of the return stroke by a universal bar 302 which overlies them, and is normally held up sufficiently to permit carrying. This bar is supported by bell cranks 303 pivoted freely on the lower tie rod 270 of the accumulator frame. Bell cranks 303 have pivotal connection to links 304 which have slots 305 in their rear ends thru which passes the rod 283. This slot connection is to give time for carrying before the rockers are returned. The bell cranks are held against immediately following rod 283 by springs 306, and upward movement of the bar 302 15 is limited by the right bell crank 303 engaging against the tie rod 283.

At the end of the rear stroke, rollers 301 ride off abutment pieces 297 and permit springs 298, 306 to return the rods 283 and 302 to normal 20 position.

Subtractive carry (Figs. 8 to 15)

In order to render the subtractive carry arms 280 effective for carrying in subtracting operations, it is necessary to shift the spring anchor rod 282 rearwardly. The means for doing this is constructed as follows:

The spring anchor rod 282 extends thru openings 307 in the accumulator frame plates 266 and 267, and has its ends supported by the upper ends of rock levers 308 pivoted to the outer sides of said accumulator frame plates. The rock levers 308 carry pins 309 near their lower ends, which pins engage in the bifurcated upper ends 35 of respective rock arms 310 fast to the accumulator frame pivot shaft 265. A spring 311 fast on the left rock arm 310 tends constantly to shift the mechanism thus far described so as to bring the spring anchor rod 282 rearwardly to 40 render subtractive arms 280 effective, but is normally prevented from doing so.

A roller 312 is mounted on the right-hand rock arm 310, and normally rests in rear of a shoulder 313 formed on a locking latch 314 pivoted on the 45 lower tie rod 270. This latch is held in locking position by a spring 315 attached to a latch 314 at one end and to an element of the total-detent mechanism to be later described.

When by any of a plurality of means to be 50 later described the latch 314 is rocked clockwise, roller 312 can escape from shoulder 313, and the anchor rod 282 can move to its rear position under impulse of spring 311, thereby rocking arms 280 to effective position for negative or 55 subtractive carrying.

Mounted on the right-hand pin 309 is a latch 316 having a tail 317 which may be depressed by a pin 318 of the continued subtracting mechanism. The latch 316 is formed with a rear 60 shoulder 319 which when pin 318 is in raised or normal position drops into the path of the extended right end of rod 283, so that as this rod 283 is moved rearwardly it restores the rod 282 and arms 280 and 279 to normal additive position. 65

The master plate (Figs. 4 to 7, 15)

Mounted fixedly on the main operating shaft 212 is a master plate 320, which controls a number of different functions of the machine as will 70 presently appear. This master plate is rocked with the main operating shaft 212, and carries a roller 321 for actuating the carriage clear-out mechanism, a roller 322 for operating the carriage return mechanism, a roller 323 concentric 75

with roller 322 for operating the carriage-return releasing mechanism, a full stroke pawl 324, a pin 325 for effecting engaging of the accumulator gears in adding operations and disengaging of the same in subtracting operations, and a wipe-pawl 326 for effecting disengaging of the accumulator gears in adding operations. The wipe-pawl 326 has other functions later set forth.

The rollers 322 and 323 might be made as a single roller, but the parts operated thereby operate at different speeds, and it is therefore more desirable to construct them as separate pieces mounted on a common pin. A spring 327 is secured at one end to the full stroke pawl 324 and at the other to an anchor pin carried by the master plate, and tends constantly to keep the pawl substantially radial. The master plate 320 is formed with a shoulder 328 which engages a stud 329 to limit movement in the forward stroke, and a shoulder 330 which engages said stud 329 to limit movement on the return stroke.

Full stroke mechanism (Figs. 4, 5, 6 and 7)

It has been described that there is a full stroke pawl 324 mounted on the master plate 320. Mounted on the stud 329 and on studs 331 and 332 from frame 103 is a full stroke segment 333, having notches or serrations 334 cut in its inner face, and lying in the plane of the full stroke pawl 324. Normally, the full stroke pawl is held some distance in rear of the segment 333, and has its end extended above the inner face of said segment.

When the forward stroke of the operating lever begins, the pawl engages segment 333 and is rocked clockwise to pass under the segment. As the stroke proceeds the pawl engages one after another of the serrations 334, and locks the operating mechanism against retrograde movement. At the end of the forward stroke the pawl enters a deep notch 335 which permits it to straighten under tension of its spring 327. On the return stroke, the pawl is moved counterclockwise, and engages serrations 334 preventing any forward stroke until the operating mechanism is returned to normal, at which time, the pawl escapes from the segment and assumes its normal position.

Operating handle shifts accumulator frame (Figs. 4, 5, 8, 14, 15, 18)

It will be remembered that the pin 325 on the master plate 320 is rocked for shifting the accumulator frame to engage accumulator gears 274 with actuating racks 253 in adding operations, and to disengage the same during subtracting operations. It will also be remembered, that cam lever 273 is the means which must be operated to rock the accumulator frame at any time that it is rocked. The connections between these two will now be described.

Secured to the cam plate 273 is a depending link 336 pivotally connected by a pin to an arm 337 of a rocker pivoted on the inner end of stud 331 of the full-stroke mechanism, which stud is extended inside plate 103 for this purpose. This rocker 337 has upper and lower arms 338 and 339 which carry laterally extending pins 340 and 341, respectively.

Slidably supported on the stud 331 and tie rod 295 is a slide bar 342 formed with upper and lower ears 343 and 344 which carry pivoted latches 345 and 346, respectively. Latch 345 may be considered the additive latch, and 346, the subtractive latch. A spring 347 tends constantly

to rotate latch 346 clockwise and latch 345 counter-clockwise. Pivoted on the right-hand end of a stud 348 carried by slide 342 is a pawl 349 formed with a shoulder 350 and normally held by a spring 351 in position to have its shoulder 350 engaged by pin 325 of the master plate when the forward stroke is nearing completion.

The other end of spring 351 is anchored to a pin 352 carried by a rock lever 353 pivoted by this same pin to the slide plate 342. Lever 353 is formed with an upstanding arm 354 which carries a spring 355 having its other end secured to a tie rod 356 between frames 103 and 105. This spring 355 tends constantly to rotate lever 353 about its pivot 352 clockwise as viewed from the right. This movement of lever 353 is limited by a lip 357 bent over from lever 353 and resting on top of slide 342.

A rear arm of lever 353 carries a roller 358 for operation by wipe pawl 326 under certain circumstances, and a depending finger at the rear end of slide 342 carries a pin 359 which extends thru frame 103 into the plane of the wipe pawl 326.

At its front end, lever 353 is formed with upper and lower arms 360 and 361 which carry rollers 362 and 363, respectively. Lower arm 361 is extended forwardly and carries a pin 364 which extends toward the right for a purpose to be later set forth.

Normally the cam lever 273 is in its upper position, and pin 362 is far enough above the additive latch 345 to permit the same to engage its jaw on pin 340 of rocker 337, while pin 363 holds the subtractive latch 346 out of active relation with its cooperative pin 341. With the parts in this position, a forward stroke of the operating lever 209 will rock master plate 320 until its pin 325 engages pawl 349 and carries slide 342 forward, carrying lever 353 forward and causing pin 340 to rock member 337 counter-clockwise, thereby drawing down link 336 and cam lever 273 so as to rock the accumulator frame clockwise and effect engagement of the gears 274 and racks 253.

The parts are maintained in normal position by a roller 365 engaging the rear notch 366 formed in the bottom of rocker 337. Roller 365 is carried by a rock lever 367, the front arm being held down by a spring 368, the lower end of which is anchored to a stationary part of the machine. When the parts are moved in an additive forward stroke as above described, roller 365 moves into a front notch 369 and holds the parts in this position until moved back again to normal.

Upon the return stroke of the operating lever 209, wipe pawl 326 engages roller 358 on the rear of lever 353 and moves the connected system of parts back to normal so that latch 345 draws rocker 337 back raising link 336 and cam lever 273, rocking the accumulator to disengaged position.

Subtracting mechanism (Figs. 4, 5, 8, 15, 14, 18)

A yoke 370 is pivotally mounted on the front tie bar 113 and carries a short rod 371 which strengthens the yoke and acts as a pivot for several members about to be described. One arm of yoke 370 extends rearwardly beyond rod 371 and is formed with a finger 372 overlaying pin 364, and carries a roller 373 which is normally engaged by the hooked lower arm 374 of a pendent latch pivoted on pin 375 to the rocker 337. This pendent latch is formed with a forwardly extending finger 376 which is normally some lit-

tle distance above the pin 311 which is extended inwardly from frame 103 into the plane of finger 376.

It should be noted in addition, the accumulator 5 is engaged at the end of the forward stroke, and is actuated upon the rear or return stroke. Also in subtraction the accumulator is thrown in before the forward stroke, actuated during the forward stroke, and thrown out at the end of the 10 forward stroke. It follows from this that in taking a total the accumulators are thrown in before the forward stroke, turned to zero on the forward stroke, and thrown out at the end of the forward stroke. Likewise, in taking a sub-total, 15 the accumulator is thrown in before the forward stroke, turned to zero during the forward stroke, returned to its former condition on the rear stroke, and thrown out toward the end of the rear stroke.

20 It may not be out of place to mention at this point that one of the main objects of the invention was to construct a machine in which no "spacing" or idle strokes are necessary between operations in any desired sequence.

25 When the subtractive mechanism is to be called into play, yoke 370 is rocked clockwise as viewed from the right, so that finger 372 presses down pin 364, rocking lever 353 anticlockwise, whereupon roller 362 moves additive latch 345 to ineffective position, and roller 363 moves down permitting spring 347 to rock subtractive latch 346 into engagement with pin 341 which has concomitantly been moved rearward.

At the same time roller 373 carries down 35 pend- 35 ent latch 374 which rocks rocker 337 until roller 365 stands in notch 369, and link 336 draws cam lever 273 down to throw the accumulator into mesh. As this movement progresses, the finger 376 strikes pin 377 and unlatches hook 374 from 40 roller 373. (The means for maintaining yoke 370 in rocked position will be described later on.) The operating lever 209 is now given a forward stroke with resulting movement of parts as described under the preceding heading, but as latch 45 345 is now ineffective and latch 346 is effective, rocker 337 is moved in a reverse direction, disengaging the accumulators toward the end of the forward stroke. While the time of actuation of the accumulators has thus been changed from the 50 return stroke to the forward stroke, carrying, whether additive or subtractive always occurs at the same point in the cycle. On the return stroke spring 355 returns the associated parts to normal additive condition so that the wipe pawl 328 passes pin 358 without touching it.

Subtracting key (Figs. 8, 14, 15)

The subtracting key button is indicated at 378 and is mounted on the upper end of a stem 379 pivotally mounted on the front end of the subtracting key-lever 380 which is pivoted on the rod 109. The stem 379 has its movement rearward limited by a pin 381 engaging a notch 382 cut in the upper edge of lever 380. Lever 380 is held up by a spring 112.

60 The shank 379 of key 378 is formed with a shoulder 383 which, when the key is depressed, may be moved rearwardly under a rib 384 secured to the guide plate 115. When thus locked 65 down it forms part of the mechanism for division or repeated subtraction.

The subtraction key lever 380 carries a pin 385 which extends into a slot in the lower end of a link 386 depending from the pin 318 carried 75 by yoke 370 of the subtracting mechanism. Also

mounted on the pin 318 is a pendent latch 387 which is constantly under the tension of a spring 388.

When the subtraction key is depressed, the pin 385 carries down link 386 and therewith the pin 318, rocking yoke 370 with results as hereinbefore described. Also latch 387 is carried down and hooks onto a pin 389 of the total key lever 390 thereby locking the yoke 370 in rocked position and locking the total key against depression. 10

As the operation progresses, the latch 387 is released by the following:

Rigidly secured to the operating shaft 212 so as to rock therewith is finger 390, and adjacent thereto is a rock arm 391 freely pivoted on shaft 15 212 and formed with a laterally bent ear 392. Pivotedly connected to the free end of arm 391 is the rear end of a link 393 near the front end of which is formed a slot 394 embracing pin 395 projecting from an arm 396 depending from the 20 hub of the right-hand member 310. Link 393 is formed with a shoulder 397 which normally stands in rear of a pin 398 on the pendent latch 387.

Upon the forward stroke of the operating lever 25 and near the end of such stroke the finger 390 contacts ear 392, rocking arm 391 and pushes link 393 forwardly until shoulder 397 strikes pin 398 and unhooks latch 387 from pin 389 whereupon latch 387 and connected parts return to 30 normal under impulse of spring 388.

Pivotedly mounted by a pin and slot connection, to link 393 is a latch 399 formed with an ear 400 which is normally held in contact with the lower edge link 393 by a spring 401. The hooked rear end of this latch normally stands in rear of pin 395 so that if the subtracting key is depressed and released, this latch 399 will return the carry spring bar 282 to additive position upon the forward stroke of the operating lever. 40

When, however, the subtract key is depressed and locked down for division or repeated subtraction the pin 385 of the subtract key lever will depress and hold latch 399 in ineffective position and bar 282 will remain in subtractive position 45 until the subtract key is released.

It will be remembered that depression of the subtract key rocks lever 353, and if the subtract key is locked down, then lever 353 will be held rocked in which condition, pin 358 cannot be operated by pawl 326. However in division or repeated subtraction, when slide 342 is moved forward the pin 358 thereof will be brought into the path of pawl 326 and operated thereby on return strokes to move slide 342 and connected 50 parts rearwardly to normal position, latch 353 55 remaining rocked until release of the subtract key.

The total key (Figs. 4, 5, 6, 8, 14, 15, 18)

The total key button 402 is mounted on the 60 total key lever 390 which is pivoted on rod 109 and held up by a spring 112. The lever 390 carries the pin 389 which extends over a hook formed on the lower end of a latch 403 depending from pin 371 of yoke 370. 65

The slot in 386 embracing pin 385 is provided so that the total key and subtract key may rock the yoke 370 without depressing each other. When the total key 402 is depressed, pin 389 70 draws down latch 403 rocking yoke 370 to throw in the accumulator. It is to be noted, that the total key depression does not effect locking of yoke 370 in moved position. Consequently, if the total key is not held down, the yoke will re- 75

turn to normal but leaving the accumulators engaged.

From this construction, it follows that if a total is to be taken, the total key must be held down so that subtractive link 346 is held engaged with pin 341 to throw the accumulator out at the end of the forward stroke. If a subtotal is to be taken, the key is depressed and released before beginning the forward stroke whereby the accumulator is held in mesh during the forward stroke and a great part of the return stroke.

Total detents (Figs. 4, 5, 8, 9, 10, 11, 12, 13, 14, 15, 18, 19)

Pivotedly mounted on the rod 269 are a plurality of total detents, one for each dial 275 and formed with hooks 404 adapted to be rocked into the paths of the carry pins 277. Each detent has a forwardly extending finger 405, and thru all of these passes a rod 406 so that all of the detents are held together to move as a unit. The right-hand finger 405 normally rests slightly below a stop finger 407 which limits the rocking of the detents, and rests on the horizontal arm of a bell crank 408 the vertical arm of which rests against a shoulder 409 on a reciprocatory bar 410 normally drawn to the left by a spring 411. A shoulder 412 of member 410 rests against an upright arm of a bell crank 413, the horizontal arm of which pivotally supports a depending link 414, the lower end of which is pivoted to the total key lever 390 at 415.

When the total key is depressed it draws down link 414 rocking bell crank 413 to draw member 410 to the right, thereby rocking bell crank 408 and the total detents so that the hooks 404 of the latter are brought into the paths of the pins 277 to stop the dials at zero position.

To lock the slide 410 in moved position for taking a sub-total, a lever 416 is pivoted to frame 103 and is formed with a finger 417 for limiting rocking movement of lever 416 by contacting frame 103. A spring 418 normally holds the finger 417 against frame 103. A pin 419 projects downwardly from slide 410 in position to be engaged by a curved finger 420 of lever 416 when the accumulator is in mesh (slide 410 being carried by the accumulator frame), and the slide moved to the right. When the total key 402 is depressed the pin 419 is locked by finger 420 and is so held until the accumulator is rocked out of mesh when pin 419 is thereby moved out of engagement with finger 420 and the slide 410 returns to normal under influence of spring 411.

Non-add key (Figs. 1, 2, 5, 6, 7, 10, 13, 14, 15)

Non-add is effected by rendering the accumulator frame shifting devices ineffective. To this end there is provided a non-add key button 421 mounted on a key lever 422 pivoted on rod 109, and held up by a spring 112. The key lever 422 carries a pin 423 which extends into the bifurcated front end of a lever 424 pivoted to the main frame 104 and having its rear end pivoted to the upper end of a short link 425, the lower end of which is pivoted to an arm 426 fast on the non-add shaft 427 having bearings in frames 103 and 104.

Near its right-hand end, shaft 427 carries an arm 428, the end of which carries a pin 429 extending into a slot formed in the lower end of a lever 430 pivoted on the inner part of stud 331, and having its upper end formed as a curved finger 431 extending over pin 432 extending leftward from the additive pawl 345.

Upon depression of the non-add key 421, pin 423 rocks lever 424, pulling up link 425, thereby rocking arm 426, shaft 427 and arm 428 clockwise, as viewed from the left. This rocks lever 430 until finger 431 depresses pin 432 moving additive latch 345 to ineffective position. Operation of the operating mechanism will now not effect throwing of the accumulator frame.

If the subtract key is depressed prior to the depression of the non-add key, it will have swung lever 337 until the extended end of pin 341 is in close proximity to the lower end of lever 430; and the rocking of lever 430 by the non-add key will move pin 341 and consequently lever 337 to accumulator-disengaging position. During this movement pin 341 is forced out of engagement from subtractive pawl 346.

It may be well at this point to note that lever 337 consists of two plates between which pawls 345 and 346 are guided, and that only the right-hand plate of this lever has a forwardly extending arm, and lower notched portion.

Clearing the differential carriage (Figs. 4, 6, 7, 8, 9, 11, 12, 13, 14, 15, 18)

A rock shaft 433 is mounted in bearings in the frames 103 and 104 and carries arms 434 fast on shaft 433 and carrying a bar or rod 435 for returning the differential stop bars 160 to normal position. A spring 436 coiled on shaft 433 and anchored at opposite ends to frame 103 and one of the arms 434 tends constantly to throw bar 435 rearward, such movement being limited by a finger 437 fast on shaft 433 engaging under a thru tie bar 438.

Secured to shaft 433 outside of frame 103 is an arm 439 which carries a forwardly extending draw bar 440 formed with a shoulder 441. A spring 442 normally holds draw bar 440 up with its front end in contact with stud 329. The front end of draw bar 440 is guided between an extension of the full-stroke segment 333 and a plate 443 supported by stud 329 and a lower stud 444.

Upon the forward stroke of operating lever 209, the roller 321 of master plate 320 is moved in rear of shoulder 441 of the draw bar 440. During the return stroke, roller 321 pulls draw bar 440 forward, rocking arm 439, shaft 433 and arms 434, thereby causing rod 435 to return the differential stop bars 160 to home or normal position. As this return stroke progresses, the roller 321 rides off shoulder 441, permitting the draw bar 440 and connected parts to return to normal under impulse of the spring 436.

Immediately thereafter, the carriage is automatically returned by means now to be described.

Automatic carriage return (Figs. 4, 6, 7, 8, 15)

It will be remembered, that the detent escape-
ment rack 159 is secured to the carriage frame. Pivotably secured to this rack is a link 445 the other end of which is pivotally connected to the end of a rearwardly extending arm 446 of a bell crank pivoted at 447 to the tie bar 191. The other arm 448 of this bell crank has its right-hand end pivotably secured to 449 to a bent-over ear 450 of a pusher bar 451. The loose connections at pivots of link 445 and at 449 permit the limited amount of arcuate movement necessary.

The pusher bar 451 extends rearwardly at the right-hand side of the machine and is formed near its rear end with a shoulder 452 adapted to be engaged on the return stroke by the roller 322 on the master plate, and returned forward thereby so as to operate the connected parts to return the carriage to normal. Pusher bar 451 is held

up by a pin 453 extending over the top of a member 454. Also bar 451 carries a roller 455 near its rear end. Member 454 is held up by a spring 456 anchored to pin 377 outside frame 103. A release member 457 pivoted on stud 329, is formed with a cam lug 458 near its rear end, and rests on roller 455. This member 457 is formed with a stop finger 459 which coacts with stud 444 to limit movement of parts 451, 454 and 457 by spring 456.

As the pusher bar 451 is returned by roller 322 it is moved until roller 323 engages cam lug 458, at which time roller 455 is under the rear end of release member 457. As roller 422 depresses the cam lug 458, this causes the release member to press down on roller 455 thereby freeing the pusher bar from roller 422 at which time the carriage is fully returned and is then held by the escapement mechanism hereinbefore described.

20 *Repeat key (Figs. 4, 6, 7, 8, 15)*

The repeat key mechanism is constructed and mounted substantially the same as the subtraction key. Thus there is a repeat key button 480, 25 rockable shank 461, locking shoulder 462 and limit pin 463 working in a notch 464 in the repeat key lever 465 pivoted on a shouldered screw which passes into and supports rod 109 and held up by spring 112. The lever 454 is formed with an 30 standing lug 466 which is bent so as to be positioned under the repeat key lever 465.

When the repeat key is depressed, its lever 465 depresses lug 466 thereby rocking release lever 454 down so its lug or lip 467 moves the front end 35 of member 440 down out of cooperative relation with roller 321 for effecting return of the differential stop bars 160. Pin 453 of carriage return bar 451 follows member 454 down, carrying shoulder 452 out of the path of roller 322, and release lever 457 follows roller 455 until lug 458 40 is out of the path of roller 323. Thus it will be seen that depression of the repeat key renders ineffective the carriage clearout and automatic carriage return mechanisms.

45 *The type segments (Figs. 4, 5, 8 to 13, 18, 20)*

Each actuator 237 is extended rearwardly and downwardly into a carrier 468 to which a type segment 469 is pivoted. The type segment 469 50 carries a pin 470 extending thru a slot 471 in its carrier 468. A spring 472 normally moves the type segment 469 so that its pin 470 stands in the front end of slot 471. Each type segment is preferably formed with type faces 473 for printing the ten digits; and each carrier is provided with teeth 474 with which an aligning bar 475 coacts.

The aligning bar 475 is carried by a pair of arms 476 loosely pivoted to the intermediate frames 105 and 106, and is drawn into the teeth 474 by a pair of hooked arms 477 freely pivoted on the tie rod 295. Each of the arms 477 is pivotally connected to the lower end of a respective link 478, the upper ends of which are pivoted on the rear ends of rock levers 479 freely pivoted on an axis member 480 supported by intermediate frames 105 and 106. The forward depending arms of levers 479 are secured together and spaced apart by two rods 481 and 482, so that members 479, 65 481 and 482 form a rigid rocking frame. Secured to the main shaft 212 are two identical cams 483, which, during forward movement of the operating lever 209, contact rod 482 and rock the levers 479 to effect movement of members 477 to 70 cam in the aligning rod 475.

Hammer mechanism (Figs. 9 to 13 and 20)

The type segments 469 are driven to print by individual hammers 484 pivoted on a rod 485 supported by frames 105 and 106.

Each hammer is formed with a contact face 486 5 for delivering a blow against the back of its type segment, a notch 487 for receiving the bent down rear edge of a universal restraining plate 488, a square pin 489, and a spring eye 490. Normally, each hammer is held by a latch 491 having a hook 492 engaging pin 489, and also by a universal return bar 493 carried by a pair of rock arms 494 free on rod 485. Each of the rock arms 494 has its hub pinned or otherwise rigidly secured to a respective downwardly extending rock arm 495, 15 and the lower end of each arm 495 is pivotally connected to the rear end of a respective curved link 496, the front ends of links 496 being pivotally connected to the bar or rod 482 of the rocking frame already described.

Each latch 491 is formed with a depending finger having a bent over ear 497 which normally stands in rear of shoulder 498 of a respective releasing dog 499, all of the dogs 499 being pivoted on the rod 480. Each dog 499 is provided with 25 a pin 500 which normally rests against the respective actuator 237 and is held depressed thereby so as to hold shoulder 498 clear of the bent over ear 497 of the respective latch 491. Springs 501 hold the releasing dogs 499 with their 30 pins 500 in contact with the actuators, and are anchored to a rod 502 carried by a pair of arms 503 loose on rod 504, the springs holding these arms with their upward extensions in contact with hubs or collars on the rod 480.

The universal restraining plate 488 has its ends bent into arms 505 pivoted to the frame members 105 and 106. The left-hand arm 505 is extended forwardly and is pivotally connected to the upper end of a depending pull bar 506 40 which is normally held up by a spring 507. The spring 507 also tends to swing the lower end of pull bar 506 forward, so that a pin 508 on the bar 506 rests upon the rear face of a rocker 509 of the non-print mechanism. In normal 45 condition, the bent over lower end 510 of the bar 506 is in the path of movement of the extended end of a pin 511 carried by the left-hand member 300 and operable by the main operating shaft.

When a number has been set up in the machine, 50 and the operating lever 209 is drawn forward, certain of the actuators will move so as to permit the respective releasing dogs 499 to rotate. This rotation will cause disengagement of the respective retaining latches 491 from their pins 489. 55 At the same time, links 496 and arms 495 and 494 will be moved to retract the universal return bar from in rear of the hammers and pin 511 will be rotated until, near the end of the forward stroke, it engages the lower end of the pull bar 60 506 and depresses the same, thereby disengaging the universal restraining plate 488 from all of the hammers so that those not still locked by latches 491 may spring rearwardly and effect printing. The distance which the releasing members 499 65 may move when free, is limited by the abutment of the front ends thereof against collars or hubs on rod 504. As bar 481 is moved forward on the forward stroke, power is stored in hammer operating springs 512 so as to cause the hammers to deliver a smart printing blow. During the return stroke, these springs return the bar 481 and connected parts to normal. It will be noted that the universal return bar 493 is considerably farther from pivot 485 than the attach- 75

ment of the springs 512 to the hammers 484, so that the springs 512 not only drive the hammers to print, but also return the hammers to normal after printing. However, if desired, additional 5 springs could be used to assist in this return movement.

Automatic zero printing (Figs. 9, 13, 20)

It is, of course, necessary that means be provided for effecting printing of zeroes to the right of the significant digits, and for this purpose, each of the latches except that of the lowest order is formed with a finger 513 which is bent to the right into the plane of the latch 491 of next lower order. It will therefore be seen that if any latch 491 is tripped its finger 513 will trip the latch of next lower order and so on to the right, whereby zeroes will be printed to the right of any significant digit printed if no significant 20 digit is set up in that order.

The non print key (Figs. 11, 12, 20)

Means are provided for preventing printing when only the accumulator actuation is desired. 25 For this purpose, there is provided a non-print key 514 secured to a key-lever 515 pivoted on rod 109 and held up by a spring 112. The key-lever 515 is formed with a depending finger 516 which is pivotally secured by a pin 517 to the lower arm of a rock lever 518 also pivoted on rod 109, and the upper arm of lever 518 is bifurcated and embraces a pin 519 carried by the rocker 509.

When the non-print key 514 is depressed, lever 515 rocks lever 518 to move pin 517 upwardly thereby rocking the rocker 509 so that it presses pin 509 rearwardly until the bent over lower end of pull bar 506 is out of the path of pin 511 and consequently no printing will be done for the universal bar 488 will prevent hammer movement.

Universal actuator return bar (Figs. 5, 11, 12, 20)

It is necessary that means be provided for returning the actuators to normal position after each excursion, and for this purpose, there is 45 provided a universal return bar 520 passing under the front ends of all of the actuators 237, and carried by a pair of rock plates 521 pivoted on rod 238, and braced by a tie rod 522. The upper end of a respective link 523 is pivoted to each of the respective rock plates 521, the lower end of each link 523 being pivoted to the front end of a respective cam plate 524. The cam plates 524 are fast to a rock shaft 525 having its bearings in the intermediate frames 105 and 106. The 55 lower faces of the cam plates 524 ride on the rollers 526 carried between the plates 300 and arms secured to the main operating shaft 212.

During the forward stroke of the operating 60 lever, rollers 526 are moved to permit the plates 524 to move downwardly, thereby permitting plates 521 to rock the universal bar 520 down to permit the actuators to make their required excursions. During the return stroke of the operating lever, the rollers 526 return the cam plates 524 to normal with a consequent upward rocking of the universal return bar 520 which returns all displaced actuators to normal.

Total key releases all of the actuators (Figs. 6, 7, 13, 14, 15, 18)

It will be remembered that when the carriage is in normal or home position, a bar 255 stands under all of the stop bars 242, so that the actuators cannot move down if an idle stroke of the

operating handle is made. When a total or a subtotal is taken, it is necessary to swing this bar back out of the path of the members 242, and for this purpose the following means is devised.

The bar 255 is held in normal position by a 5 spring pressed rod 261 as hereinbefore described, and the right-hand end of this rod is bent down at 527 and stands in rear of a spring pressed pawl or pusher 528 pivoted to the bottom of a foot 529 bent over from a depending leg 530 of 10 the total key-lever 390.

When the total key 402 is depressed, it rocks lever 390, thereby moving pawl 528 rearwardly against element 527 rocking rod 261 and thereby moving plate 255 rearwardly to ineffective position. Upon the ensuing operation of the operating lever, all of the actuators may move down under control of the accumulators and total-detent mechanism as already described.

However, when a sub-total is taken, the total key is depressed and immediately released, and therefore there is provided a spring-pressed latch 531 pivoted on an ear bent out from the carriage frame, and normally resting against the element 527. When the total key is depressed, and the element 527 is swung back, it is caught and held in this position by the latch 531, until near the end of the return stroke of the ensuing operation of the operating lever. It is to be remembered that the carriage return mechanism draws the 30 carriage some little distance to the right of home position before releasing the carriage, and this is taken advantage of to release 527 from latch 531. While the carriage has not moved from normal position during the total taking operation, 35 the carriage return mechanism is operated near the end of the return stroke, drawing the carriage slightly to the right, thereby striking the tail of pawl 531 against the right side frame 103 and rocking it to release element 527 which springs 40 back to normal position. As the carriage is released and drops back to home position, the latch 531 again comes into contact with the element 527.

Sign printing (Figs. 14, 18, 20, 21, 22)

It is desirable to print signs to indicate total, sub-total, subtraction, division (continued subtraction) and non-add operations. For this purpose, there is provided a sign type-carrier 532 50 which carries a sign type segment 533 provided with five sign type. It will be noted that that portion of the segment 533 which is in alignment with the zeroes of the number printing segments has no type face, as the sign printing is not controlled from the numeral printing segments (as by an automatic zero device), and its hammer is only released when segment 533 moves up one or more steps. The hammer mechanism for the sign printing segment 533 is identical with that 55 for the number printing segments except that there is no control from the automatic zero mechanism, and this mechanism will not be further described.

The signs are arranged on the segment 533 65 with the sub-total sign 534 in line with the "1" type of the numeral print-segments, the total sign 535 in line with the "2" type, the subtraction sign 536 in line with the "3" type, the division sign 537 in line with the "4" type, and the 70 non-add sign 538 in line with the "5" type. From this it will be seen that the carrier 532 and segment 533 must be moved one step for printing the sub-total sign, two steps for printing the total sign, three for subtraction, four for division and 75

five for non-add, and the means for this purpose will now be set forth.

The front end of carrier 532 is cut off, as it carries no actuating rack, and at this front end is pivoted a depending link 533 similar to the stop bars 242, and provided with springs 244. The member 533, is however, formed with a shoulder 540 extending rearwardly into the plane of a differential stop segment 541, and in normal condition of the machine is prevented from following tie bar 522 by the uppermost or longest stop shoulder of this segment.

The segment 541 is pivoted to the rear side of bar 239 and is constantly under tension of a spring 542 which tends to rotate segment 541 counter-clockwise as viewed from the rear such movement being limited to the position shown in Fig. 21 by reason of the connected linkage about to be described.

Secured to the segment 541 is the lower end of a link 543, the upper end of which is pivotally secured to a rocker 544 pivoted to frame 185 outside of the right hand plate 249. The front end of rocker 544 is pivotally connected to a depending link 545 the lower end of which is connected to a rocker 546 fast on the sign shaft 547. Normally an upper finger 548 contacts the top of bar 239 thereby limiting movement of segment 541 by spring 542. The rocking of the shaft 541 by the various keys which control sign printing shifts the segment 541 so as to bring a respective shoulder 549 into the path of movement of the shoulder 540.

It will be remembered that when the total key 402 is depressed it causes arm 370 to rotate clockwise as viewed from the right, depressing pin 364. Pin 364 extends over the front arm of a bell-crank 550 and when pin 364 is pressed down by depression of the total key this pin rocks the bell-crank 550, said bell-crank being secured to the sign-shaft 547. Consequently the sign shaft is also rocked, and, if the total key is held depressed, the shaft 547 is rocked far enough to bring its second shoulder 549 into active position so that the sign-segment may move two steps so as to effect printing of the total sign. If, however, the total key is depressed and released, for taking a sub-total, pin 364 is permitted to rise so that the bell-crank 550 can return one step of movement, this distance being determined by the engagement of a roller 551 with a shoulder 552 on a spring-pressed rocker 553 pivoted on rod 109. The upper end of rocker 553 carries a pin 554 which extends into the plane of member 337, and is returned to normal ineffective position nearby. With the pin 551 resting against shoulder 552, the first shoulder 549 is effective and the sub-total sign will be printed.

When the subtracting key 378 is depressed and locked in depressed position, it moves the arm 370 and consequently pin 364 and bell-crank 550 a considerably greater distance than depression of the total key. With the subtracting key locked down the sign shaft 547 will have been rocked so as to bring the fourth stop 549 into effective position, so that the division sign will be printed. If, however, the subtract key is depressed and then released the parts are allowed to move back slightly thereby rendering the third stop 549 effective so that the subtraction sign will be printed.

It will be remembered that when the non-add key is depressed, it effects rocking of the shaft 421. Secured to this shaft is an arm 555 which carries a pin 556 passing thru a slot in the front

end of a link 557, the rear end of which is pivotally secured to an arm 558 fast on the sign shaft 547. The pin and slot connection at 556 is to permit rocking of the sign shaft without rocking the non-add shaft.

When the non-add key is depressed, the linkage just described effects rocking of the sign shaft 547 until a lower finger 559 of rocker 546 contacts bar 239, at which time the lowest shoulder 549 is effective and in the ensuing operation of the machine, the non-add sign will be printed.

Paper carriage (Figs. 4, 23, 24)

The paper carriage includes right and left side frames 560 and 561 which have notches 562 and 563 for engaging tie rods 564 and 565, 565 being a thru tie rod and the two tie rods 564 passing from respective outer frames to respective intermediate frames. Latches 566 pivoted on frames 560 and 561 coact with notches 562 to lock the carriage to the tie rods, but may be manually moved rearwardly so that the carriage may be readily removed from the machine. The rods 567 and 568 and a paper guide 569 rigidly secure the frames 560 and 561 together as a unit. A roll of paper 570 is supported by a rod 571 having a thumb nut 572 for unscrewing the same from the frames.

A paper-pan or curved guide 573 is secured to tie rod 567 and curves around the platen 574 in close proximity thereto so as to guide the paper between the platen 574 and a presser roll 575. The platen is supported on a rod 576 having bearings in the carriage frames 560 and 561, said rod 576 being provided with the usual thumb knobs 577. The presser roll 575 is mounted on a rod 578 carried by a pair of rock levers 579 pivoted loosely on the tie rod 567 and having their rear ends connected by a rod 580. Springs 581 secured to depending ears of levers 579 and anchored to tie rod 568 press roller 575 toward the platen. By pressing forwardly on rod 580 the presser roller may be moved away from the platen against the tension of springs 581.

The upper edge of paper guide 569 is serrated to form a paper cutter, and the body of guide 569 is formed with an opening 582 thru which the type print.

Paper feed mechanism (Figs. 11, 12, 23, 24)

Secured to the platen shaft 576 is a paper feed ratchet wheel 583 normally engaged by a detent roller 584 carried between a pair of bell-cranks 585 pivoted on tie rod 567 and urged to force roller 584 against ratchet wheel 583 by a spring 586. Pivoted on the inner face of the left side frame 561 is a rock lever 587 which carries a roller 588 at its lower end and a pivoted ratchet pawl 589 at its upper end. A spring 590 tends constantly to rock the lever 587 with its shoulder 591 contacting a collar on tie rod 567. With the lever in this position, the pawl 589 is retracted rearwardly, and if the lever 587 is then rocked forwardly, the pawl will carry the ratchet wheel with it thus spacing the paper.

The roller 588 of lever 587 presses against the rear end of a slide bar 592 formed with slots by which it is slidably supported on tie rod 565, and rod 485, with its front end in the path of pin 511. During the forward stroke of the operating lever, pin 511 moves forward permitting slide bar 592 to follow under impulse of the lever 587 from spring 590, thereby retracting pawl 589. On the return stroke, the pin 511 forces slide bar 592 rearwardly, thereby rocking lever 587 and forcing pawl 589 forward to effect paper feed.

A plate 593 is loosely pivoted on the platen shaft 576 and is pressed toward frame 561 by a spring 594. This plate is formed with a finger-piece 595 by which it may be rotated to any one of four positions. With the finger-piece 595 in its foremost position, the paper will be fed a double space at each operation of the machine. By moving the finger piece to the rear one space, the paper will be fed only one space at each 10 operation. By moving the finger-piece to the rear another step there will be no automatic paper feed, and by throwing the fingerpiece to rearmost position, there will be no paper feed and the detent roller 584 will be rendered ineffective 15 so that the platen may be turned freely by hand any desired amount.

The plate 593 is formed with a cam lug 596 which coacts with a pin 597 on pawl 589 to hold the pawl ineffective during a portion or all of its travel when single spacing or non-spacing is desired, and is also formed with a cam lug 598 which is adapted to engage the extended end of the pin of the detent roller when the finger-piece is in rearmost position, thereby rendering the detent ineffective. The plate 593 is held in its several positions by the rounded head of a pin 597 in frame 561 engaging in respective indentations 599 in the lefthand face of the plate 593.

30 Bichrome ribbon mechanism (Figs. 20 and 22)

Between the platen and the printing type segments is a bichrome ribbon 600, the upper part of which is preferably black (or some dark color), and the lower portion of which is red. When printing numbers which are being added, printing is done from the upper portion of the ribbon which is normally at the printing line, and when printing totals, subtotals, amounts subtracted, repeated subtraction, or numbers printed but not added, printing is done from the lower portion of the ribbon. It will be noted that in all cases where the numbers are to be printed from the lower portion of the ribbon, the sign printing segment 533 is moved to print a sign. This is taken advantage of to control shifting of the ribbon from one position to the other.

Projecting from the sign printing carrier 532 toward the right is a pin 601 which normally rests on the right-hand one of a pair of ribbon vibrating arms 602 pivoted on shaft 238 and having their rear portions secured together by a tie bar 603. These arms 602 have upwardly extending ribbon carrying fingers 604, and are urged in a counter-clockwise direction (as viewed from the right), by springs 605. Forwardly extending ears 606 rest above bar 522, the latter serving to return the ribbon vibrator to normal at the end of any sign-printing operation. The vibrator is held in normal position during adding operations by the pin 601 from the sign printing carrier 532. Upward movement of the vibrator is limited by a pin 607 contacting the bar 608 which is slotted to guide the levers 602 and the spring ears of the several actuators and the sign carrier.

It will therefore be seen that the ribbon is normally held to print from the upper portion thereof, and that whenever there is an operation involving movement of the sign printing segment, 533 the ribbon is vibrated to position to print from the lower portion of the ribbon.

Ribbon feed and reverse mechanism (Figs. 11, 12, and 22)

75 Means is provided for feeding the ribbon trans-

versely and for automatically reversing the direction of feed when the ribbon on either spool nears exhaustion.

The ribbon is wound upon two spools 609 which are provided with depending shouldered pins 610 which extend into apertures in disks 611 secured to ribbon-feed shafts 612 supported in brackets and pressed downwardly by springs 613. Secured to the lower ends of the shafts 612 are beveled gears 614 which are adapted to be engaged by 10 respective beveled gears 615 fast on a ribbon drive shaft 616 slidably mounted in bearings in the frames 105 and 106 and limited as to sliding movement by collars or other suitable means. Only one of the gears 615 may be in engagement 15 with its gear 614 at a time, so that one or the other of the shafts 612 may be actuated to feed the ribbon 600 and the other is free to permit unwinding of the ribbon from its spool. The shaft 616 is shiftable longitudinally by means to be presently set forth, and is held in either position by the rounded lower end of the left-hand shaft 612 entering one or the other of the two grooves 617 cut in the extending portion of shaft 616. The spring 613 on this shaft permits such 20 movement, and the spring 613 on the right-hand shaft 612 presses the lower end of the same into engagement with the shaft 616 so as to frictionally prevent retrograde movement of shaft 616 upon return of its actuating pawl now to be 25 described.

Secured to shaft 616 is a ratchet wheel 618 which is adapted to be engaged and driven by a ratchet pawl 619 during the return stroke of the operating handle. The pawl 619 is broad enough to engage the wheel 618 in both positions of shaft 616 and is pivoted to member 592 with which it moves. It is spring pressed upwardly by a spring 620. It will therefore be seen that at each reciprocation of the bar 592, pawl 619 will effect turning of the shaft 616 and consequent feeding of the ribbon in one direction or the other according to which of the gears 615 is engaged.

Rotatably mounted in brackets in the frames 105 and 106 are ribbon reversing rods 621 each of which carries a ribbon follower 622 rigidly secured to its upper end and pressing against the ribbon on a respective spool 609. Each rod 621 has its lower end bent laterally, then downwardly and then laterally. At the first lateral bend a spring 623 is attached which constantly tends to rotate the respective rod to press its follower against the ribbon. The gears 615 have their inner ends formed with beveled faces 624.

As the ribbon is unwound from a spool, its follower 622 gradually moves in under influence of its spring 623 until the lower end of its rod 621 is moved into coaction with the beveled face 624 of its respective gear. Further turning of the 60 shaft 616 causes this face to ride against the lower end of the respective rod 621 thereby forcing the gear and shaft axially until this gear engages its gear 614 and the shaft has moved the other gear 615 out of mesh. The ribbon is 65 now fed onto the empty (or nearly empty) spool until the other nears exhaustion, when the other rod 621 becomes effective to shift back again. In this manner the ribbon is automatically reversed.

One other point needs to be explained, and that is, that when division is to be done, it is necessary to lock down the repeat key as well as the subtraction key. The reason for this is that the differential stop carriage must not be auto- 75

matically returned until the operation is completed, and the repeat key renders the carriage return mechanism ineffective as already described. Also for multiplication, the repeat key 5 alone is locked down.

While I have described what I consider the most desirable embodiment of my invention, I do not limit myself to the precise details, nor to anything less than the whole of my invention as 10 hereinbefore described.

I claim:

1. In a machine of the class described, the combination with an accumulator and actuators therefor, of a transversely movable carriage, a 15 plurality of differential stop bars slidably mounted on said carriage and each formed with a plurality of stepped actuator stopping shoulders, a plurality of digit keys, and means settable by said digit keys for effecting movement of said stop bars 20 to positions representing numbers for controlling said actuators comprising a set of key levers, transversely slidable bars controlled thereby, a slidable rack member controlled by said slide bars, and a connecting gear mechanism cooperating 25 between said slidable rack member and said differential stop bars.

2. In a machine of the class described, the combination with an accumulator and actuators therefor, of a transversely movable carriage, a 30 plurality of differential stop bars slidably mounted on said carriage and each formed with a plurality of stepped actuator stopping shoulders, springs for moving said stop bars, dogs for retaining said stop bars against movement by said springs, 35 a plurality of digit keys, and means operable by said keys for releasing said dogs and controlling movement of said stop bars comprising a set of key levers, transversely slidable bars controlled thereby, a slidable rack member controlled 40 by said slide bars, and a connecting gear mechanism cooperating between said slidable rack member and said differential stop bars.

3. In a machine of the class described, the combination of digit keys, respective key slides 45 operable by said digit keys, a universal bar controllable by said slides as to extent of movement, a tiltable shaft and gear controllable as to rotation by said universal bar, a carriage, a plurality of differential members carried thereby, and means for moving said carriage to bring any one 50 of said differential members into cooperative relation to said tiltable shaft.

4. In a machine of the class described, the combination of digit keys, respective key slides 55 operable by said digit keys, a universal bar controlled by said slides as to extent of movement, a tiltable shaft and gear controllable as to rotation by said universal bar, a carriage, a plurality of differential members carried thereby, 60 means for moving said carriage to bring any one of said differential members into cooperative relation to said tiltable shaft, and an escapement mechanism operable by said keys for controlling movement of said carriage.

5. In a machine of the character set forth, the combination of an accumulator, actuators therefor, a transversely movable carriage, a normal 65 stop member on said carriage, and normally in position to prevent operation of any of said actuators, a plurality of differential stop members on said carriage and movable therewith to positions to control movement of said actuators, each stop member being formed with a plurality of stepped actuator stopping shoulders, and means 70 for moving said differential stop members on 75

said carriage to set up representations of numbers to be entered on said accumulator comprising a set of digit keys and key levers, a similar set of digit slide bars, a single rack slide controlled thereby, and a gear mechanism cooperating between said rack slide and said differential stop members in sequence. 8

6. In a machine of the class described, the combination of an accumulator, actuators therefor, a plurality of differential stop slides each 10 formed with a plurality of digital actuator stopping shoulders, a carriage for said slides, slide setting mechanism comprising a set of keys and key levers, a set of key-controlled digital slides, a setting rack controlled thereby, and a gear 15 mechanism cooperating between said rack and said stop slides, operating mechanism, and means operable by said operating mechanism for returning said differential stop slides to normal position. 16

7. In a machine of the class described, the combination of an accumulator, actuators therefor, a plurality of differential stop slides each formed with a plurality of digital actuator stopping shoulders, a carriage for said slides, slide setting mechanism comprising a set of keys and 20 key levers, a set of key-controlled digital slides, a setting rack controlled thereby, and a gear 25 mechanism cooperating between said rack and said stop slides, operating mechanism, and means operable by said operating mechanism for returning said differential stop slides to normal position, and for returning the said carriage to normal position. 30

8. In a machine of the class described, the combination of an accumulator, actuators therefor, a plurality of differential stop slides each 35 formed with a plurality of digital actuator stopping shoulders, a carriage for said slides, slide setting mechanism comprising a set of keys and key levers, a set of key-controlled digital slides, a setting rack controlled thereby, and a gear 40 mechanism cooperating between said rack and said stop slides, operating mechanism, and means operable by said operating mechanism for returning said differential stop slides to normal position, and for returning said carriage to normal 45 position and releasing said carriage. 36

9. In a machine of the class described, the combination of an accumulator, actuators therefor, a plurality of differential stop slides each 50 formed with a plurality of digital actuator stopping shoulders, a carriage for said slides, slide setting mechanism comprising a set of keys and key levers, a set of key-controlled digital slides, a setting rack controlled thereby, and a gear 55 mechanism cooperating between said rack and said stop slides, operating mechanism, means ap- 60 erable by said operating mechanism for returning said differential stop slides to normal position and for returning said carriage to normal position and means for rendering the first said means ineffective. 65

10. In a machine of the class described, the combination, including a set of accumulator members, actuators therefor, comprising rotatable gear sectors having printing members attached thereto, a transversely movable carriage comprising a plurality of differential stop bars 70 slidably mounted thereon, each stop bar comprising a rack portion, a stepped portion adapted to cooperate with said actuators and releasable catch members cooperating with said rack portion, a plurality of digit keys, and mechanism co- 75 operating between said digit keys and said stop bars, comprising a set of digit key stops, a co- 80

operating slide member having a rack thereon, and a tilttable shaft and gear mechanism operable by said rack adapted to release said catch members and to control differential displacement of said stop bars.

5 11. In a machine of the class described, the combination of a plurality of accumulator wheels, a single set of digit keys for the ultimate control thereof, a set of operation control keys adapted 10 to control the cooperation between said accumulator wheels and said digit keys, a set of digit slides cooperating with said digit keys, a single slide member adapted to be digitally adjusted by said digit slides, said digit slides being adapted 15 to prevent the operation of more than one digit key at a time, a plurality of settable stop bars, a gear system cooperating between said stop bars and said single slide, a carriage for the support of said stop bars, said digit slides, single slide 20 and gear train serving for the adjustment of a plurality of stop bars from said single set of digit keys for the operation of said plurality of accumulator wheels.

25 12. In a computing machine, the combination of a plurality of depressible keys, a respective key lever for each of said keys, a plurality of slotted slide bars positioned underneath said respective key levers and at right angles thereto, means comprising cam members respectively cooperating 30 each with one of said key levers and one of said slotted bars whereby each of said slotted bars is transversely moved by a corresponding key lever and all other key levers are locked in unmoved position, and a sliding rack member cooperating 35 with a moved slotted bar.

13. In a computing machine, the combination of a plurality of depressible keys, a respective key

lever for each of said keys, a plurality of slotted slide bars positioned underneath said respective key levers and at right angles thereto, means comprising cam members respectively cooperating each with one of said key levers and one of said slotted bars whereby each of said slotted bars is transversely moved by a corresponding key lever and all other key levers are locked in unmoved position, a sliding rack member cooperating with a moved slotted bar, a gear and shaft cooperating 10 with said rack a second gear on said shaft, and a plurality of settable stepped slide members co-operating with said shaft and second gear and positioned thereby.

15 14. In a computing machine, the combination of a plurality of depressible keys, a respective key lever for each of said keys, a plurality of slotted slide bars positioned underneath said respective key levers and at right angles thereto, means comprising cam members respectively cooperating 20 each with one of said key levers and one of said slotted bars whereby each of said slotted bars is transversely moved by a corresponding key lever and all other key levers are locked in unmoved position, a sliding rack member cooperating 25 with a moved slotted bar, a gear and shaft cooperating with said rack a second gear on said shaft, a plurality of settable stepped slide members cooperating with said shaft and second gear and positioned thereby, a movable carriage for 30 the support of said stepped slide members, an actuating lever, and means actuated from said actuating lever for moving said carriage and restoring said slide members to unoperated position.

LOUIS M. LLORENS. 35
